UNITED STATES PATENT OFFICE

143,315

DESIGN FOR A MARBLE RUNWAY TOY

Glenn B. Hatcher, Tulsa, Okla.

Application May 25, 1945, Serial No. 119,719

Term of patent 7 years

(Cl. D34—15)

To all whom it may concern:

Be it known that I, Glenn B. Hatcher, a citizen of the United States, residing at Tulsa, in the county of Tulsa and State of Oklahoma, have invented a new, original, and ornamental Design for a Marble Runway Toy, of which the following is a specification, reference being had to the accompanying drawing, forming part thereof.

The figure is a perspective view of a marble runway toy showing my new design.

I claim:

The ornamental design for a marble runway toy, as shown.

GLENN B. HATCHER.
